STENCILING APPARATUS

Lawrence O. Mankin and Leonard D. Soubier,
Toledo, Ohio, assignors to Owens-Illinois Glass
Company, a corporation of Ohio

Application April 30, 1938, Serial No. 205,264

17 Claims. (Cl. 101—124)

The present invention relates to stenciling apparatus and more particularly to a fully automatic stenciling machine designed to decorate the cylindrical sides and tapered shoulder portions of bottles, specifically milk bottles. The principles of the invention are applicable to other uses and the stenciling machine may be employed in the decoration of other articles having curved surfaces such as tumblers, jars and the like.

It is among the principal objects of the invention to provide a stenciling apparatus which will apply a decoration or lettering to opposite sides of bottles both in the cylindrical side regions thereof and in the tapered shoulder portions thereof, the process involving four separate and independent decorating operations on the bottle with independent decorating instrumentalities for each operation, thus permitting the application 20 of designs or lettering in four different colors if desired.

An equally important object of the invention is to provide such an apparatus in which certain of the decorating instrumentalities have associated therewith reciprocable stencil screens for applying the decorations or lettering to the cylindrical sides of the bottles and in which others of the decorating instrumentalities have associated therewith oscillatable stencil screens for applying the decorations or lettering to the tapered shoulder portions of the bottles, all of the stencil screens being operable to apply the decorations or lettering to the bottles when moving in either direction, thus obviating distortion of the screen 35 in the manner characteristic of screens which perform the decorating operation in only one direction.

In carrying out the above mentioned objects, the invention contemplates the provision of a 40 fully automatic stenciling machine which will receive the bottles in an inclined position at a receiving zone and which will convey the same successively through a first decorating zone wherein a set of stenciling instrumentalities are brought into action to apply a vitreous enamel composition to the tapered shoulder portions of each bottle on one side of the mold seam by the spreading action of a squeegee which forces the enamel through the previous portions of a stencil screen. 45 From the first decorating zone the bottles are successively conveyed to a second decorating zone and, upon approaching this latter zone, the bottles assume a recumbent position for proper cooperation with a set of decorating instrumentalities in the second zone which apply a decoration

or lettering to the cylindrical side of each bottle on the other side of the mold seam. In moving to a third decorating zone, the bottles remain in their recumbent position and in passing through the third zone a decoration or lettering is applied 5 to the undecorated side of each bottle by another set of decorating instrumentalities. Finally, in moving to a fourth decorating zone, the bottles are again inclined and a set of decorating instrumentalities in this last zone applies a decoration or lettering to the undecorated shoulder portion of each bottle.

Another object of the invention is to provide a decorating machine of the character set forth above in which there is incorporated a plurality 15 of independent decorating instrumentalities designed for successive cooperation with successive bottles in the machine and which are bodily movable in the direction of movement of the bottles passing therebeneath and at the same rate of 20 speed in order that the bottles may be decorated while moving continuously at a constant rate of speed from the initial point of introduction to the apparatus to the point of discharge thereof.

Other objects of the invention, not at this time 25 particularly enumerated, will become apparent as the nature of the invention is better understood and the same consists in the novel combination, construction and arrangement of parts shown in the accompanying drawings, in which:

Fig. 1 is a top plan view of a stenciling apparatus manufactured in accordance with the principles of the present invention;

Fig. 2 is an enlarged fragmentary top plan view of a portion of the apparatus in the vicinity of 35 a decorating zone;

Fig. 3 is an enlarged fragmentary top plan view of a portion of the apparatus in the vicinity of another decorating zone;

Fig. 4 is a sectional view taken substantially 40 along the line 4—4 of Fig. 2;

Fig. 5 is a sectional view taken substantially along the line 5—5 of Fig. 3;

Fig. 6 is a sectional view taken substantially along the line 6—6 of Fig. 5;

Fig. 7 is an enlarged sectional view taken substantially along the line 7—7 of Fig. 4;

Fig. 8 is a sectional view similar to Fig. 7, showing the parts thereof in a different position;

Fig. 9 is a sectional view taken substantially 50 along the line 9—9 of Fig. 5;

Fig. 10 is a sectional view similar to Fig. 9, showing the parts thereof in a different position;

Fig. 11 is an enlarged sectional view taken substantially along the line 11—11 of Fig. 4;

Fig. 12 is a sectional view similar to Fig. 11, showing the parts thereof in a different position;

Fig. 13 is an enlarged transverse sectional view taken through a control valve employed in connection with the present invention;

Fig. 14 is a sectional view similar to Fig. 13, showing the valve parts in a different position;

Fig. 15 is a sectional view taken substantially along the line 15—15 of Fig. 14; and

Fig. 16 is a sectional view taken substantially along the line 16—16 of Fig. 15.

The stenciling machine involves in its general organization an endless conveyor 20 (Figs. 1 and 4) including upper and lower conveyor chains 21 and 22 respectively which are adapted to be moved continuously in unison at a predetermined rate of speed. The chains 21 and 22 are mounted upon and driven by power driven sprockets 23, 24 and 25, 26 respectively at opposite ends of the conveyor thus eliminating any tendency of the chains to become slack in the medial regions of the conveyor on either side thereof. Tracks 35 or supports underlie the chains 21 and 22 in the medial regions of the conveyor and constitute a portion of the stationary framework 30 of the machine.

The sprockets 23 and 25 are disposed at the receiving and discharge end of the conveyor and are mounted upon a common vertical shaft 27 which is rotatably supported in antifriction bearings, one of which is shown at 28, the bearings being supported on an extension 29 forming a part of the stationary framework 30. The sprockets 24 and 26 are disposed at the other end of the conveyor and are similarly mounted in antifriction bearings, one of which is shown at 41 and which is carried on an extension 42 also forming a part of the stationary framework 30. The sprockets 24 and 26 are disposed at the other end of the conveyor and are similarly mounted in antifriction bearings, one of which is shown at 41 and which is carried on an extension 42 also forming a part of the stationary framework 30.

The two driving shafts 27 and 40 are driven in common in any suitable manner from a suitable source of power such as an electric motor (not shown).

Still referring to Figs. 1 and 4, a plurality of bottle supporting units U are connected to the upper and lower conveyor chains 21 and 22 at spaced points therearound and each unit has associated therewith a tiltable bottle chuck assembly C which is adapted to convey a bottle B placed thereon at a receiving and discharging zone Z successively past a series of bottle decorating zones Z¹, Z², Z³ and Z⁴. At the first decorating zone Z¹ a set of decorating instrumentalities D¹ is adapted to apply decorations or letterings to the bottles B in passing, the decorations or letterings being applied to the tapered shoulder portions of the bottles on one side of the mold seams. At the second decorating zone Z² a second set of decorating instrumentalities D² is adapted to apply decorations or letterings to the bottles on the opposite sides of the mold seams and on the cylindrical body portions of the bottles. Decorating instrumentalities D³ and D⁴, similar to the decorating instrumentalities D² and D¹, at the decorating zones Z³ and Z⁴ respectively, are adapted to apply decorations or letterings to the cylindrical sides or body portions of the bottles on the first decorated sides thereof and to the shoulder portions thereof on the other sides of the bottles.

Referring now to Figs. 2 and 4, each bottle supporting unit U includes an angular support 43 providing a table portion 44 and a vertical attachment portion 45 by means of which the support 43 is secured to the conveyor chains 21 and 22. The outer end of the support 43 is supported upon a continuous track 46 which extends around the conveyor 20 and which is supported upon a series of standards 37 and which is also supported from the support 61. In the straight-away portions of the conveyor the track 46 is of channel-shape in order that the units U may be maintained in parallelism. In the end regions of the conveyor the track 46 is flat to permit the units U to swing as they pass around the ends of the conveyor.

The bottle supporting chuck assembly C consists of a tiltable plate 49, which is pivoted as at 50 to the plate 43 and which is provided with opposed guideways 51 and 52 between which there is slidably disposed a slide member 53 upon which there is rotatably mounted a head chuck 54. The base chuck 55 is rotatably mounted on the plate 49 and is designed to cooperate with the head chuck 54 in rotatably supporting a bottle B therebetween in such a manner that its axis is parallel to the plane of the plate 49. A coil spring 36 normally urges the slide member 53 inwardly of the plate 49 and thus, when it is desired to insert or remove a bottle in or from the chuck assembly C, it is merely necessary for the operator to force the head chuck 54 outwardly, using the rim of the bottle for this purpose, and remove the bottle from or place the same in the chuck assembly.

Referring to Figs. 1 and 4 it will be seen that when the bottle supporting units U are in the vicinity of the first and forth decorating zones Z¹ and Z⁴ respectively, the plates 49 associated therewith assume inclined positions thus causing the bottles B to become inclined and present their tapered shoulder portions horizontally to the decorating instrumentalities D¹ or D⁴ as the case may be. Toward this end, each plate 49 carries at its inner end a roller 56 which cooperates with the underneath side of a rail 57 which is supported from the stationary framework 30 and which extends from a point forwardly of the fourth decorating zone Z⁴ to a point rearwardly of the first decorating zone Z¹ in the direction of travel of the units U.

Continuing reference to Figs. 1 and 4, the decorating instrumentalities D¹ at the first decorating zone Z¹ are substantially identical with the decorating instrumentalities D⁴ at the decorating zone Z⁴ and a description of the former will suffice for the latter. Either set of instrumentalities comprises a slidable supporting block 60 which is capable of reciprocation in a direction parallel to the direction of movement of the units U on the conveyor 20 while passing the decorating instrumentalities. The supporting block 60 is slidably disposed on a support 61. A dovetail tongue and groove connection 62 is provided between the block 60 and the support 61. A short standard 63 is mounted upon the block 60 and is laterally adjustable thereon by virtue of clamping bolts 64 which extend through slots 65 formed in the base 66 of the standard 63 and which are anchored in the block 60. A tubular sleeve 67 secured to the standard 63 adjustably receives therein one end of a rod 68 which, in turn, adjustably receives thereover the lower end of a supporting rod 69. A portion of the rod 69 extends vertically and this vertical portion has 75

rotatably mounted thereon a sleeve 10 on which there is formed a gear 11. A two-piece split collar 12 secured to the sleeve 10 has one portion thereof formed integral with a pair of stencil 5 screen supporting arms 13, the latter supporting therebetween a screen frame 14 to which there is secured a conventional stencil screen 15. A squeegee supporting bracket 16 is pivoted for swinging movement in a vertical plane to 10 the rod 69 and a squeegee 17 is adjustably suspended from the lower end of the bracket 16. The bracket 16 is normally maintained in its lowermost position with a squeegee 17 in contact with the screen 15 by means of a coil spring 18 15 which is disposed between the bracket and an overlying arm 19 formed on a collar 20 adjustably secured to the rod 69.

In order to oscillate the stencil screen frame 14 and cause the screen 15 to be moved to and 20 fro across the shoulder portions of successive bottles B passing therebeneath with the screen in tangential rolling line contact with the bottles, the gear 11 meshes with a reciprocable toothed rack 21. The rack 21 is adapted to be periodically actuated by means of a fluid actuated piston and cylinder assembly 22 including a piston 23 to which the rack 21 is connected and a cylinder 24. The piston and cylinder assembly 22 is carried at the upper end of a bracket 25 25 which is adjustably secured by means of clamping bolts 26 which extend through a slot 27 formed in the bracket 25 to a standard 28 similar to the standard 29 and similarly secured to the supporting block 30. Opposite ends of the 30 cylinder 24 are connected by means of flexible conduits 31 and 32 to a control valve V¹, the 35 operation of which will be set forth presently.

In order to elevate the squeegee from the stencil screen at the end of each decorating operation 40 as is the usual custom in stencil screen decoration, a pair of cam members 33 positioned on the screen frame 14 engage the bracket 16 as the screen approaches the end of its decorating stroke in either direction to tilt the bracket slightly and 45 cause the squeegee to clear the enamel decorating composition placed upon the screen.

The support 34 is provided with a limit stop 48 at one end thereof which determines one extreme position of the block 30. A cord 49 passes 50 over a pulley 50 and is attached to a weight 51 by means of which the block 30 is normally moved to its extreme position in engagement with the limit stop 48. In order that the squeegee 17 shall during the decorating operation contact the stencil screen 15 along the shifting line of contact 55 between the bottle and screen, a spring pressed detent 52 (see also Fig. 7) projects outwardly from the table portion 44 of the support 33 and is adapted to engage a portion of the block 30 provided 60 with a notch 53 at one corner thereof. During such engagement between the detent 52 and block 30, the latter is moved with the former and at the same rate of speed, the squeegee 17 following the movement of the bottle B in 65 decorating relation thereto. The detent 52 has secured thereto a roller 54 which is designed for engagement with a cam member 55 positioned in its path. Upon completion of each decorating operation the roller 54 engages the cam member 55 and is moved inwardly of the support 33, carrying with it the detent 52 which is drawn clear of the notch 53, thus permitting the weight 51 to 70 return the block 30, together with the decorating instrumentalities carried thereby, to its initial 75 position in engagement with the limit stop 48

ready for advancement when the next unit U comes into decorating relation at the decorating zone Z¹.

During the decorating operation on one bottle the stencil screen is adapted to move in one direction, while during the decorating operation on the next succeeding bottle the screen is adapted to move in the other direction. Thus there is no lost motion of the screen nor is the screen obliged to bear the weight of the squeegee 10 except when a bottle is in decorating position therebeneath to receive the full thrust of the latter. Toward this end the control valve V¹ is supported from the framework 30 and is adapted to be engaged successively by a series of trip fingers 15 100 formed on the various plates 43 to change the position of the valve instrumentalities and periodically direct compressed air or other fluid medium to the alternate ends of the cylinder 24. 20

Referring now to Figs. 11 to 16 inclusive, 25 wherein the valve V¹ and its associated actuating instrumentalities are shown, the valve includes a casing 101 which is substantially cylindrical in design and in which there is mounted for rotation a rotor 102. A series of ports 103, 104, 105 and 106 30 are formed in the casing 101 and adjacent ports are designed to be periodically connected together by means of passages 107 and 108 provided through the rotor 102. The port 103 is connected by means of a conduit 109 to the atmosphere. The port 104 is connected by means of the flexible conduit 87 to one end of the cylinder 24. The port 105 is connected by means of a conduit 111 to a source (not shown) of compressed air. The port 106 is connected by means 35 of the flexible conduit 86 to the other end of the cylinder 24. When the ports 103 and 104 are in communication through either passage 107 or 108, the other passage establishes communication between the ports 105 and 106. Thus air is admitted to one end of the cylinder 24 from the conduit 111 while the other end of the cylinder is exhausted through the conduit 109. The rack 21 is moved to one extreme position thereof while the stencil screen 15 is oscillated, performing its 40 decorating stroke in one direction as it moves, and assumes one of its extreme positions. Upon movement of the rotor throughout an angle of ninety degrees, the ports 104 and 105 are brought into communication by one of the passages 107 or 108 and the other passage connects the ports 106 and 103. With the rotor in this position, air is admitted to and exhausted from the cylinder 24 in such a manner as to reverse the position of the rack 21 and oscillate the screen 15 to the other 45 extreme position thereof during which oscillation the screen performs its decorating stroke in the opposite direction. 50

The control valve V¹ is adapted to be actuated by movement of the bottle supporting units U on the conveyor 20 past the first decorating zone Z¹ and toward this end the rotor 102 has formed thereon a stem 115 (Figs. 15 and 16) which is provided with a plurality of ratchet teeth 116 arranged ninety degrees apart. A spring pressed 55 detent 117, housed within a boss 118 provided in an oscillatable casing 119 mounted on the stem 115, bears against the latter. The casing 119 has formed thereon a bifurcated torque applying lever 120 and a roller 121 supported between the 60 bifurcations of the lever 120 is positioned directly in the path of movement of the series of fingers 100 (see also Fig. 4), one of which is formed on each of the supports 43. A torque spring 123 65 concentric with the casings 101 and 119 is 70 75

anchored at its opposite ends to these casings and normally urges the casing 119 to an initial position in which the lever 120 is in engagement with a limit stop 124 formed on the casing 101. It will be seen therefore that each time one of the fingers 100 engages the roller 121 the casing 119 is moved angularly to the position indicated in Fig. 11, and, upon release of the roller 121, the casing is restored to its initial position as shown in Fig. 12 preparatory to being engaged by the next succeeding finger 100 as shown in dotted lines in this figure. Such periodic and successive oscillation of the casing 119 operates in the manner previously described to index the rotor 102 throughout an angle of ninety degrees, thus actuating the stencil screen and causing periodic oscillation thereof alternately in opposite directions.

Referring now to Figs. 1, 3 and 5, after the units U leave the first decorating zone Z¹ in progressing to the second decorating zone Z² with the bottles thereon decorated in the tapered shoulder portions thereon on one side of the mold seams, the rollers 56 successively move out of engagement with the underneath side of the rail 57 and, upon thus being released, the tiltable plates 49 fall by gravity to positions in contact with the table portions 44 of the supports 43. The bottles B thereon are thus caused to assume a recumbent position in order that the cylindrical sides thereof may properly be presented for decoration at the second decorating zone Z² by the decorating instrumentalities D².

It is to be noted that during the decorating operation at the first decorating zone Z¹ the bottles B are rotated throughout an angle of one hundred and eighty degrees by virtue of the tangential rolling line contact between the bottles and the screen 75. Alternate bottles passing the decorating zone Z¹ are rotated in opposite directions by virtue of their contact with the screen but the result is the same inasmuch as the extent of rotation in each instance is precisely one hundred and eighty degrees.

The decorating instrumentalities D² at the zone Z² are substantially identical with the decorating instrumentalities D³ at the decorating zone Z³ and a description of the former will suffice for the latter. Both of these sets of decorating instrumentalities are similar in many respects to the decorating instrumentalities D¹ and D⁴ and either set D² or D³ comprises a slideable supporting block 130 (Figs. 1, 3 and 5) which is capable of reciprocation in a direction parallel to the direction of movement of the units U upon the conveyor 20 while passing the decorating instrumentalities. The supporting block 130 is slideably disposed on a support 131 forming a part of the stationary framework 30. A dovetail tongue and groove connection 132 is provided between the block 130 and the support 131. The block 130 has formed thereon an upwardly projecting standard 133 upon which a fluid actuated piston and cylinder assembly 134 including a piston 128 and a cylinder 129 is adjustably mounted. Piston rods 135 connected to the piston 128 project from the opposite ends of the cylinder 129 and are connected by means of arms 136 to a stencil screen frame 137 having a stencil screen 138 secured thereto. In order to reciprocate the stencil screen 138 in its own plane, means is provided for alternately admitting air under pressure to the opposite ends of the cylinder 129 and toward this end these ends of the cylinder 75 are connected by conduits to a control valve V²

(or V³ in the case of the decorating instrumentalities D³) which is identical with the control valve V¹ shown in Figs. 13, 14, 15 and 16. The control valve V² (or V³) is designed for cooperation with the fingers 100 formed on the supports 43 to reciprocate the stencil screen 138 in the manner previously described. Toward this end the control valve is connected to the cylinder by means of flexible conduits 139 and 141.

A squeegee 140 is adjustably suspended from a squeegee arm 141 which is pivoted to a lug 143 formed on the cylinder 129. A spring 144 normally maintains the squeegee 140 in decorating contact with the stencil screen 138. Cam members 145 similar to the cam members 96 take care of squeegee elevation at the end of each decorating stroke of the screen.

In order that the squeegee 140 shall, during the decorating operation, contact the stencil screen 138 along the shifting lines of contact between the bottles and screen, a spring pressed detent 146 (Fig. 9) projects inwardly from each support 43 and is adapted to engage a portion of the block 130 provided by a notch 160 at one corner thereof. During such engagement between the detent 146 and block 130, the latter is moved with the former at the same rate of speed, the squeegee following the movement of the bottle B in decorating relation thereto. The detent 146 has secured thereto a roller 152 which is designed for engagement with a cam member 153 positioned in its path. Upon completion of each decorating operation, the roller 152 engages the cam member 153 and is moved inwardly of the support 43, carrying with it the detent 146 which is drawn clear of the notch 160. A weight 150, which is attached to a cord 148 that passes over a pulley 149 and is attached to the block 130, returns the block 130 to its initial position in contact with a limit stop 147.

As previously stated, the decorating instrumentalities D³ and D⁴ are identical in their character and function and operation with the decorating instrumentalities D² and D¹ respectively and no further description thereof is necessary, it being sufficient to state that during the decorating operation in each of the decorating zones Z¹, Z² and Z³ the bottles B are rotated throughout an angle of one hundred and eighty degrees so that the bottles B are completely reversed prior to presentation at the next succeeding decorating zone. Thus bottles introduced at the receiving and discharging zone Z are alternately decorated on opposite sides of the mold seams and are alternately decorated on the shoulder portions and cylindrical side portions thereof without danger of contamination of the wet decorations previously made when the bottles arrive at a succeeding decorating zone.

In order to bring the tapered shoulder portions of the bottles B into decorating contact with the stencil screen 75 in the decorating zone Z⁴, the rail 57 extends to a point forwardly of this fourth decorating zone and is designed for contact with successive rollers 56 prior to arrival of the units U at the zone.

The stenciling apparatus is capable, without any modification whatsoever, of applying decorations or letterings to the cylindrical sides and tapered shoulder portions of two series of bottles simultaneously, the bottles being simultaneously introduced into the machine and removed therefrom by two operators, one stationed at each end of the conveyor 20. In such an instance, bottles B proceeding from the receiving and discharging

zone Z at one end of the conveyor toward the other end thereof are decorated first in the tapered shoulder regions thereof by the decorating instrumentalities D¹ and are subsequently 5 decorated in the cylindrical body portions thereof by the decorating instrumentalities D². Simultaneously, bottles proceeding in the opposite direction on the other side of the conveyor 20 are decorated first in the cylindrical body portions 10 thereof by the decorating instrumentalities D³ and subsequently are decorated in the tapered shoulder regions thereof by the decorating instrumentalities D⁴. Each operator removes the bottles introduced by the other operator from the 15 machine at his own respective receiving and removal zone.

In order that the decorations shall extend completely around the bottles in both the shoulder and body portions thereof, it is necessary to substitute 20 stencil screens having a three hundred and sixty degree sweep across the surface of the bottle during the decorating operation, and in such an instance a different color may be employed for the decorations or lettering applied to the shoulder and body portions of the bottles respectively.

Modifications may be resorted to within the spirit and scope of the appended claims.

We claim:

1. In an apparatus for decorating articles having curved surfaces by a stenciling process, decorating instrumentalities for applying decorations to the articles in a decorating zone including a reciprocable stencil screen and a relatively stationary squeegee therefor, means for reciprocating 30 said stencil screen, means for continuously and successively moving a series of articles through said zone, and means for bodily moving said decorating instrumentalities in decorating relation to the articles passing through the zone.

2. In an apparatus for decorating articles having cylindrical surfaces by a stenciling process, decorating instrumentalities for applying decorations to the articles in a decorating zone including a reciprocable stencil screen and a relatively 45 stationary squeegee therefor, means for continuously and successively moving a series of articles through said zone, means for bodily moving said decorating instrumentalities in decorating relation to the articles passing through said zone, 50 and means for reciprocating said stencil screen relative to the squeegee during such movement of the decorating instrumentalities bodily.

3. In an apparatus for decorating articles having cylindrical surfaces by a stenciling process, 55 decorating instrumentalities for applying decorations to the articles in a decorating zone including a reciprocable stencil screen and a relatively stationary squeegee therefor, means for continuously and successively moving a series of articles through said zone, means operable by movement 60 of the articles through said zone for bodily moving said decorating instrumentalities in decorating relation to the articles passing through said zone, and means for reciprocating said stencil screen relative to the squeegee during such movement of the decorating instrumentalities bodily.

4. In an apparatus for decorating articles having curved surfaces by a stenciling process, 70 decorating instrumentalities for applying decorations to the articles in a decorating zone including a reciprocable stencil screen and a relatively stationary squeegee therefor, means for continuously and successively moving a series of articles through said zone, means for bodily moving 75 said decorating instrumentalities in decorating

relation to and in register with the articles passing through said zone, fluid pressure means including a piston for reciprocating the screen during such movement of the decorating instrumentalities bodily, a control valve for reciprocating the piston, and means operable by movement of the articles through said zone for actuating said control valve.

5. In an apparatus for decorating articles having curved surfaces by a stenciling process, 10 decorating instrumentalities for applying decorations to the articles in a decorating zone including an oscillatable stencil screen and a relatively stationary squeegee therefor, means for continuously and successively moving a series of articles through said zone, means for bodily moving said 15 decorating instrumentalities in decorating relation to and in register with the articles passing through said zone, fluid pressure means including a piston for oscillating the screen during such 20 movement of the decorating instrumentalities bodily, a control valve for reciprocating the piston, and means operable by movement of the articles through said zone for actuating said control valve.

6. In an apparatus for decorating articles having curved surfaces by a stenciling process, 25 decorating instrumentalities for applying decorations to the articles in a decorating zone including a movable stencil screen and a relatively stationary squeegee therefor, means for continuously 30 and successively moving a series of articles through said zone, means for bodily moving said decorating instrumentalities in decorating relation to and in register with the articles passing 35 through said zone, fluid pressure means including a piston for moving the screen during such movement of the decorating instrumentalities bodily, a control valve for reciprocating the piston, and means operable by movement of the 40 articles through said zone for actuating said control valve.

7. In an apparatus for decorating articles having curved surfaces by a stenciling process, 45 decorating instrumentalities for applying decorations to the articles in a decorating zone including a movable stencil screen and a relatively stationary squeegee therefor, a movable support upon which said instrumentalities are operatively mounted, a plurality of article supporting units 50 each including means for rotatably supporting an article thereon, means for moving said units successively through the decorating zone, means carried by each unit for engaging said support and moving the same through the decorating zone 55 with the decorating instrumentalities in decorative relation to the article thereon, means for moving the screen relative to the squeegee during movement of the support to apply a decoration to the article, and means for returning the support to its initial position after the decoration 60 has been applied to the article.

8. In an apparatus for decorating articles having curved surfaces by a stenciling process, 65 decorating instrumentalities for applying decorations to the articles in a decorating zone including a movable stencil screen and a relatively stationary squeegee therefor, a movable support upon which said instrumentalities are operatively mounted, a plurality of article supporting units 70 each including means for rotatably supporting an article thereon, means for moving said units successively through the decorating zone, means carried by each unit for engaging said support and moving the same through the decorating zone 75

with the decorating instrumentalities in decorative relation to the article thereon, a piston, fluid pressure means including a control valve for reciprocating the piston, means connecting the piston and screen whereby movement of the former transmits motion to the latter, means carried by each unit for actuating the control valve, and means for returning the support to its initial position after the decoration has been applied to the article.

9. In an apparatus for decorating articles having curved surfaces by a stenciling process, decorating instrumentalities for applying decorations to the articles in a decorating zone including a reciprocable stencil screen and a relatively stationary squeegee therefor, a movable support upon which said instrumentalities are operatively mounted, a plurality of article supporting units each including means for rotatably supporting an article thereon, means for moving said units successively through the decorating zone, means carried by each unit for engaging said support and moving the same through the decorating zone with the decorating instrumentalities in decorative relation to the article thereon, means for reciprocating the screen relative to the squeegee during movement of the support to apply a decoration to the article, and means for returning the support to its initial position after the decoration has been applied to the article.

10. In an apparatus for decorating articles having curved surfaces by a stenciling process, decorating instrumentalities for applying decorations to the articles in a decorating zone including a reciprocable stencil screen and a relatively stationary squeegee therefor, a movable support upon which said instrumentalities are operatively mounted, a plurality of article supporting units each including means for rotatably supporting an article thereon, means for moving said units successively through the decorating zone, means carried by each unit for engaging said support and moving the same through the decorating zone with the decorating instrumentalities in decorative relation to the article thereon, a piston, means connecting the piston and screen whereby movement of the former will transmit reciprocal motion to the latter, a control valve for causing reciprocation of the piston, means carried by each support for actuating the control valve, and means for returning the support to its initial position after the decoration has been applied to the article.

11. In an apparatus for decorating articles having curved surfaces by a stenciling process, decorating instrumentalities for applying decorations to the articles in a decorating zone including an oscillatable stencil screen and a relatively stationary squeegee therefor, a movable support upon which said instrumentalities are operatively mounted, a plurality of article supporting units each including means for rotatably supporting an article thereon, means for moving said units successively through the decorating zone, means carried by each unit for engaging said support and moving the same through the decorating zone with the decorating instrumentalities in decorative relation to the article thereon, a piston, means connecting the piston and screen whereby movement of the former will transmit oscillatory motion to the latter, a control valve for causing reciprocation of the piston, means carried by each support for actuating the control valve, and means for returning

the support to its initial position after the decoration has been applied to the article.

12. In an apparatus for applying decorations to the tapered shoulder portions and cylindrical sides of bottles and like articles, decorating instrumentalities for applying decorations to the articles in a first decorating zone including a horizontally oscillatable stencil screen, decorating instrumentalities for applying decorations to the articles in a second decorating zone including a horizontally reciprocable stencil screen, a plurality of article supporting units each including means for rotatably supporting an article, means for moving said units successively through the decorating zones in succession, means operable upon such movement of the units for tilting the supporting means to bring the tapered shoulder portions of the articles into tangential rolling line contact with the screen in the first decorating zone and to bring the cylindrical sides thereof into tangential rolling line contact with the screen in the second decorating zone, means operable upon movement of the units for oscillating the screen in the first decorating zone, and means operable upon movement of the units for reciprocating the screen in the second decorating zone.

13. In an apparatus for applying decorations to bottles, and endless conveyor, a plurality of bottle supporting units mounted on the conveyor in spaced relationship, decorating instrumentalities for applying decorations to the bottles in a decorating zone, a movable support upon which said decorating instrumentalities are mounted, means normally urging said support into an initial position of rest, means carried by each unit and normally projecting into the path of movement of the support for engaging the latter to move the same through the decorating zone with the decorating instrumentalities in decorative relation to the bottle thereon, means for retracting said engaging and moving means after the support has passed through the decorating zone, and means for actuating said decorating instrumentalities during movement of the support through the decorating zone.

14. In an apparatus for applying decorations to the tapered shoulder portions and cylindrical sides of bottles, decorating instrumentalities for applying decorations to the tapered shoulder portions of the bottles in each of two decorating zones, decorating instrumentalities for applying decorations to the cylindrical sides of the bottles in each of two additional decorating zones, a plurality of bottle supporting units each including means for rotatably supporting a bottle, means for continuously moving said units successively through the decorating zones in succession, means operable upon movement of said units for tilting the supporting means to bring the tapered shoulder portions of the bottles carried thereby into decorating relation with the decorating instrumentalities in the two first mentioned zones and to bring the cylindrical sides thereof into decorating relation with the decorating instrumentalities in the two last mentioned zones, and means operable upon movement of the units for actuating the decorating instrumentalities.

15. In an apparatus for decorating the tapered shoulder portions and the cylindrical sides of bottles, decorating instrumentalities for applying decorations to the tapered shoulder portions of the bottles in a decorating zone including an oscillatable stencil screen and a relatively sta-

- tionary squeegee therefor, decorating instrumentalities for applying decorations to the cylindrical sides of the bottles in another decorating zone including a reciprocable stencil screen and 5 a relatively stationary squeegee therefor, means for continuously and successively moving a series of articles through said zone, means for bodily moving the decorating instrumentalities in each zone in decorating register with the articles 10 passing through the zone, and means for moving the stencil screen of each set of decorating instrumentalities relative to its respective squeegee during movement of the decorating instrumentalities bodily.
- 15 16. In an apparatus for decorating the tapered shoulder portions of bottles, decorating instrumentalities for applying decorations to the shoulder portions of the bottles including a horizontally oscillatable stencil screen, means including 20 a rack and pinion for oscillating said screen, a cylinder, a reciprocable piston disposed in the cylinder, means connecting said piston and rack, means for supplying motive fluid to the opposite ends of the cylinder, a control valve for con-

trolling the admission of motive fluid to the opposite ends of the cylinder, means for successively passing a series of bottles beneath said screen in decorative relation to the screen, and means operable upon movement of the bottles beneath said screen for actuating said control means. 5

17. In an apparatus for decorating articles having curved surfaces by a stenciling process, decorating instrumentalities for applying decorations to the articles in a decorating zone including a stencil screen movable in opposite directions and a relatively stationary squeegee therefor, means for continuously and successively moving a series of articles in one direction through said zone, means for bodily moving 10 said decorating instrumentalities in the same direction with successive articles passing through the zone in decorating relation thereto, and means for moving the screen relative to the squeegee alternately in opposite directions during movement of successive articles through the zone. 15 20
